OPEN STITCH SEWING MACHINE

Jacob Brussell, New York, N. Y., assignor to
Isadore Friedman, Roselle, N. J.

Application August 13, 1937, Serial No. 158,869

12 Claims. (Cl. 112—179)

This invention relates to sewing machines, more particularly to a mechanism whereby several pieces of fabric may be sewed together by an open stitch, more often termed a "ladder stitch" or "faggoting".

It is highly desirable in many cases for decorative and other purposes to sew two or more pieces of fabric together with an open stitch. This in the past has been accomplished by hand, which is a very slow process, or by machines which were capable of forming such stitches but the mechanism thereof was complicated and delicate or slowed down the operation of the machine to such an extent that it could not be used in commercial large scale production.

The present invention is intended and adapted to overcome the disadvantages and difficulties heretofore encountered in machines of this type and to provide a simple mechanism which is easily held in place, which may be adjusted for different widths of stitches to be made, which is readily removable, and which is strong and sturdy.

In practicing the present invention, I provide a sewing machine with the usual stitch-forming mechanism, but substitute in place of the ordinary single needle plate a multiple needle plate having the parts thereof in vertically, superposed, parallel relationship. I also provide a corresponding number of feed dogs and presser feet similarly arranged. In one of the needle plates and one of the presser feet there is a slot extending from the needle opening to the rear, whereby the pieces of fabric after having been sewed may be freely fed through the machine without interference by reason of the stitches.

In the accompanying drawing, constituting a part hereof, and in which like reference characters indicate like parts:

40 Fig. 1 is a longitudinal sectional view through the stitch-forming mechanism of a sewing machine, showing the present invention in place;

Fig. 2 is a transverse sectional view thereof taken along the line 2—2 of Fig. 1;

45 Fig. 3 is an enlarged perspective view of a modified form of presser foot arrangement; and

Fig. 4 is a plan view of two pieces of fabric sewed together by the mechanism of the present invention.

50 The usual sewing machine, comprising a bed 1, having a hook 2 beneath the same suitably operated, is provided with the usual head 3 having a needle bar 4 and a presser foot bar 5 arranged for operation as usual.

55 Two needle plates 6 and 7 in superposed rela-

tion and substantially parallel to each other are joined together by means of an upstanding portion 8 secured to or integral with needle plate 6. One or more screws 9 passing through an edge of needle plate 7 holds the same on top of portion 5. 8. In order to adjust the distance between plates 6 and 7, shims or plates of predetermined size may be interposed between needle plate 7 and portion 8.

Adjacent to portion 8, a slot 10 is provided in 10 needle plate 6 and a corresponding slot 11 directly above the same is provided in needle plate 7. To hold the feed dog arrangement, there is provided a base 12 mounted as usual, having a link 13 pivoted thereto, the free end of said link 15 being secured to rock shaft 14 driven in the ordinary manner. The lower feed dog 15 of the feed dog arrangement is suitably secured to base 12. At the side thereof, adjacent to portion 8, there is fitted to said feed dog 15 or integrally formed 20 therewith, an upstanding portion 16 which passes through slot 10. A second feed dog 17 in superposed relation to feed dog 15 and parallel thereto has a side extension fitted onto the top of portion 16 by one or more screws 18. In 25 order to adjust the distance between the feed dogs 15 and 17, shims or plates may be interposed between portion 16 and feed dog 17. Suitable openings are provided in needle plates 6 and 7 to allow functioning of the feed dog 15 and 17, 30 respectively.

A series of needle openings 19 are provided in the several parts to allow the passage of the needle 20 therethrough.

There is further provided a pair of presser 35 feet 21 and 22 also in superposed, parallel relationship, the lower presser foot 21 being interposed between plates 6 and 7 and the upper presser foot being above plate 7. They are bound together by upstanding portion 23 terminating in 40 a flattened plate 24, whereby the presser foot arrangement may be secured to bar 5 by screw 25. The lower presser foot 21 is provided with a slot starting at needle opening 26 and terminating at 27 at the rear of said presser foot. 45

Similarly, the upper needle plate 7 is provided with a slot which starts at needle opening 19 and extends rearwardly to 27' at the rear of said needle plate.

In Fig. 3 I have shown a slight modification of 50 the presser foot arrangement which allows of adjustability of the distance between presser feet 21 and 22. In this modification the upper presser foot 22 is provided with an upstanding portion 28 at one side thereof. Vertical slots 29 therein 55

are adapted to receive screws 30 which pass through said slots and into portion 23 of the presser foot arrangement. By suitable manipulation of the screws 30, the relative positions of 5 presser feet 21 and 22 may be adjusted.

In the operation of the machine, when two pieces of fabric are to be joined by a ladder stitch, a piece of fabric is placed on each of the needle plates 6 and 7, the presser feet 21 and 22 10 are lowered in position, and the machine is operated. The cooperation of the needle 20 and hook 2 causes a line of stitching to be made with a separation between the fabrics equal to the 15 distance between plates 6 and 7. By reason of the slots 27 and 27', the rearward movement of the fabric by the feed dogs is not interfered with and the sewed fabric freely passes out of the mechanism. The resulting product is shown 20 in Fig. 4. The pieces of fabric 31 and 32 are 25 provided with in-turned portions or hems 33 with a series of stitches 35 in parallel spaced relationship with the pieces of fabric spaced a desired distance apart. To some extent, the spacing may be changed by regulating the tension 30 of the thread during the sewing. By increasing the tension, the pieces of fabric are brought closer together by reason of the tightening of the stitch, and by decreasing the tension of the thread there is less tightening of the stitch and 35 the pieces of fabric are not drawn so closely together. If a considerable change in the spacing between the fabrics is desired, then the device itself may be adjusted. For instance, the presser feet may be adjusted as described in connection 40 with Fig. 3 and the needle plates and feed dogs may be adjusted by the introduction or removal of shims, as described above.

Although I have described my invention setting forth several embodiments thereof, it will be noted 45 that variations may be made therein without departing from the principles herein set forth. For instance, the invention is not confined to the sewing of two pieces of fabric together with a ladder stitch, but a greater number 50 may be sewed together by the provision of additional needle plates and the like. The means for adjusting the distance between the pairs of elements may be quite different from those described and if desired, the several pairs of elements 55 may be permanently secured together or may be integrally formed. These and other changes in the details of construction may be made within the spirit of the invention, the scope of which is defined in the claims appended hereto.

What I claim is:

1. In a sewing machine, stitch forming mechanism, a plurality of needle plates in superposed relation having needle openings therein, a corresponding 60 number of superposed feed dogs, openings in said plates for the reception of said dogs and means for simultaneously operating the same, a corresponding number of superposed presser feet having needle openings therein and means for simultaneously operating the same.

2. In a sewing machine, stitch forming mechanism, a plurality of needle plates in superposed relation having needle openings therein, a corresponding 65 number of superposed feed dogs, openings in said plates for the reception of said dogs and means for simultaneously operating the same, a corresponding number of superposed presser feet having needle openings therein and means for simultaneously operating the same, 70 one of said needle plates and one of said presser

feet having a slot extending from the needle opening to the rear end thereof.

3. In a sewing machine, stitch forming mechanism, a plurality of needle plates in superposed relation having needle openings therein, a corresponding 5 number of superposed feed dogs, openings in said plates for the reception of said dogs and means for simultaneously operating the same, a corresponding number of superposed presser feet having needle openings therein and 10 means for simultaneously operating the same, the upper needle plate and the lower presser foot having a slot extending from the needle opening to the rear end thereof.

4. In a sewing machine, stitch forming mechanism, a plurality of needle plates in superposed relation having needle openings therein, a corresponding 15 number of superposed feed dogs, openings in said plates for the reception of said dogs and means for simultaneously operating the same, a corresponding number of superposed presser feet having needle openings therein and 20 means for simultaneously operating the same, said feed dogs and presser feet being respectively secured together.

5. In a sewing machine, stitch forming mechanism, a plurality of needle plates in superposed relation having needle openings therein, a corresponding 25 number of superposed feed dogs, openings in said plates for the reception of said dogs and means for simultaneously operating the same, a corresponding number of superposed presser feet having needle openings therein and 30 means for simultaneously operating the same, said feed dogs being secured together along one side and said presser feet being secured together 35 along the opposite side.

6. In a sewing machine, stitch forming mechanism, a plurality of needle plates in superposed relation having needle openings therein, a corresponding 40 number of superposed feed dogs, openings in said plates for the reception of said dogs and means for simultaneously operating the same, a corresponding number of superposed presser feet having needle openings therein and 45 means for simultaneously operating the same, the distance between said plates being sufficient to allow raising and lowering of said presser feet.

7. In a sewing machine, stitch forming mechanism, a plurality of needle plates in superposed relation having needle openings therein, a corresponding 50 number of superposed feed dogs, openings in said plates for the reception of said dogs and means for simultaneously operating the same, a corresponding number of superposed presser feet having needle openings therein and 55 means for simultaneously operating the same, said feed dogs and needle plates being respectively secured together along one side and said presser feet being secured together along the 60 opposite side.

8. In a sewing machine, stitch forming mechanism, a plurality of needle plates in superposed relation having needle openings therein, a corresponding 65 number of superposed feed dogs, openings in said plates for the reception of said dogs and means for simultaneously operating the same, a corresponding number of superposed presser feet having needle openings therein and 70 means for simultaneously operating the same, said feed dogs being secured together along one side and an opening in at least one of said plates to allow passage of said securing means.

9. In a sewing machine, stitch forming mechanism, a plurality of needle plates in superposed 75

relation having needle openings therein, a corresponding number of superposed feed dogs, openings in said plates for the reception of said dogs and means for simultaneously operating the same, a corresponding number of superposed presser feet having needle openings therein and means for simultaneously operating the same, and means for adjusting the distance between the said feed dogs, presser feet and needle plates respectively.

10. In a sewing machine, stitch forming mechanism, a plurality of needle plates in superposed relation having needle openings therein, a corresponding number of superposed presser feet having needle openings therein, and means for feeding fabric over said needle plates.

11. In a sewing machine, stitch forming mech-

anism, a plurality of needle plates in superposed relation having needle openings therein, a corresponding number of superposed presser feet having needle openings therein, and means for feeding fabric over said needle plates, one of said needle plates and one of said presser feet having a slot extending from the needle opening to the rear thereof.

12. In a sewing machine, stitch forming mechanism, a plurality of needle plates in superposed relation having needle openings therein, a corresponding number of superposed presser feet having needle openings therein, said presser feet being secured together, and means for feeding fabric over said needle plates.
